UNITED STATES PATENT OFFICE.

FREDERICK W. TOLFREE, OF BELLEVILLE, NEW JERSEY, ASSIGNOR TO JOSEPH DIXON
CRUCIBLE COMPANY, OF JERSEY CITY, NEW JERSEY, A CORPORATION OF NEW JERSEY.

DESIGN FOR A PENCIL-CASE OR SIMILAR ARTICLE.

42,553.

Specification for Design.

Patented May 21, 1912.

Application filed January 25, 1912. Serial No. 673,456. Term of patent 14 years.

To all whom it may concern:

Be it known that I, FREDERICK W. TOLFREE, a citizen of the United States, residing at Belleville, in the county of Essex and State of New Jersey, have invented a new, original, and ornamental Design for Pencil-Cases or Similar Articles, of which the following is a specification, reference being had to the accompanying drawing, forming part hereof.

The figure is a plan view of a pencil case showing my new design.

I claim:—

The ornamental design for a pencil case or similar article as shown.

FREDERICK W. TOLFREE.
